UNITED STATES PATENT OFFICE.

HERBERT L. MEEDER, OF DENVER, COLORADO, ASSIGNOR OF ONE-HALF TO LEWIS S. HALL, OF DENVER, COLORADO.

INTERNAL-COMBUSTION ENGINE.

1,310,919.

Specification of Letters Patent. Patented July 22, 1919.

Application filed February 11, 1918. Serial No. 216,527.

To all whom it may concern:

Be it known that I, HERBERT L. MEEDER, a citizen of the United States, residing at the city and county of Denver and State 5 of Colorado, have invented certain new and useful Improvements in Internal-Combustion Engines; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 My invention relates to improvements in internal combustion engines, my object being to provide a construction of this class which shall contain a number of improvements over engines of this class heretofore 20 in vogue so far as I am aware. One feature of my improvement consists in the construction whereby the explosive mixture is subjected to a double compression within the cylinder, the charge of mixture being 25 drawn into the cylinder below the piston during the upward or outward movement thereof and compressed during the downward stroke before the intake port above the piston is opened, after which the previously 30 compressed mixture rushes into the cylinder above or beyond the piston and just before the explosion takes place. The initial compression of the explosive mixture within the cylinder below the piston serves 35 to produce a more nearly perfect mixture, since the gasoline or other fluid employed is vaporized or thoroughly intermingled with the air or oxygen, before entering the explosion compartment of the cylinder above 40 the piston, where it is again compressed immediately prior to the explosion, as heretofore indicated.

This is a two-cycle engine, that is to say 45 an explosion takes place for every complete reciprocation of a piston as distinguished from a four cycle engine where two complete reciprocations of the piston occur for each explosion which takes place. Hence, in a four cylinder engine, for instance, I get 50 as many explosions for an equal number of piston reciprocations, as occur in an eight cylinder four cycle engine.

Another feature of my improvement consists in means for automatically lubricating 55 the cylinders and pistons during the opera-

tion of the engine, an oil duct being provided which leads from the chamber of the crank case to an exterior offset portion of the cylinder, whereby an annular cavity is formed around the piston as soon as the latter begins its inward movement. Again, the inner head of each cylinder is provided with a sleeve through which the piston stem passes, the piston being provided with an annular cavity around the stem to receive this sleeve, this cavity being closed by the approach of the outer end of the hollow piston during its inward movement. However, during the outward movement of the piston, this cavity gradually opens with the result 65 that a partial vacuum is formed, whereby lubricating vapor or fluid is drawn into the said cavity through a longitudinal passage in the piston stem which communicates at one extremity with the chamber of the crank 70 case and at its opposite extremity with the outer end of the cavity in the piston.

Other features of novelty will be set forth in detail as this specification proceeds.

Having briefly outlined my improvement 80 I will now describe the same in detail reference being made to the accompanying drawing in which is illustrated an embodiment thereof. In this drawing:

Figure 1 is an elevation of my improved 85 internal combustion engine shown partly in section and partly in elevation, the left hand side being shown in central longitudinal section through the cylinders, while the right hand side is in elevation.

Fig. 2 is a cross section taken on the line 2-2, Fig. 1 looking toward the right.

Fig. 3 is an enlarged fragmentary section illustrating the check valve-controlled induction port.

Fig. 4 is a fragmentary section taken through the outer portion of one of the pistons but shown on a larger scale than in Figs. 1 and 2.

Fig. 5 is a view looking in the direction 100 of arrows 5, Fig. 4.

The same reference characters indicate the same parts in all the views.

Let the numeral 5 designate the crank case of my improved internal combustion 105 engine and 6 the crank shaft, the cranks 7 being connected through the medium of pitmen 8 with cross heads 9 slidably in guide casings 10 which are open at their lower extremities. The cross head extremi- 110

ties of the pitmen 8 are jointed to the cross heads 9 to permit the necessary oscillating movement incident to the connection of the pitmen with the cranks of the shaft, while the crossheads move in the guide casings in a direct line. Each cross head is rigidly connected with the inner extremity of a piston stem 12 which passes through an opening 13 in the top of the crank case and 5 registering opening 14 in the inner head 15 of each cylinder 16, the outer extremity of the stem extending through a central annular cavity in the piston 18, the outer extremity of the stem being secured, as shown at 17, to the outer end of the piston. The inner head 15 of each cylinder is provided with an outwardly extending sleeve 19 through which the piston stem passes, the said sleeve extending outwardly beyond 10 the head far enough to remain in the cavity of the piston when the latter is at its outward limit of movement, as shown at the extreme left of Fig. 1. The piston stem is perforated longitudinally to form a passage 20 which communicates at its inner extremity with the chamber of the crank case and at its outer extremity through a port 21 with the cavity 22 of the piston. By virtue 25 of this construction oil or vapor oil is drawn from the crank case into the cavity 22 by virtue of the fact that as the piston moves outwardly within the cylinder, the cavity 22 is gradually opened beyond the outer extremity of the sleeve 19, with the result 30 that a partial vacuum is formed in the cavity 22 into which the necessary oil is drawn from the crank case for purposes of lubrication.

Again, the cylinder is provided intermediate its extremities with an offset 23 which enlarges the chamber inwardly beyond the offset and toward the crank case, as shown at 24, the piston having a corresponding offset at its inner end. When the piston is 40 at its outward limit of movement, the cavity or space 24 is practically closed, while as the piston begins its inward movement this space is gradually opened, and oil or vapor of oil from the crank case is drawn thereinto by virtue of vacuum formed in the said space, the oil passing to the space 24 through a relatively small conduit 25, one extremity of which communicates with the top of the crank case chamber while its opposite extremity communicates with the outer end 45 of the space 24. By virtue of the construction just described, it is evident that my improved engine is provided with a vacuum system for automatic lubrication. The 50 splash in the crank case produces sufficient oil vapor or fog in the air in the case for proper lubrication.

Each cylinder is in communication at its inner extremity with a port 26 which in turn 55 is in communication with the chamber 27

of a valve casing 28, the port 26 being controlled for purposes of intake by a valve 58 whose stem 29 engages the bent end 30 of a rod 31 connected in operative relation with an eccentric cam 32, whereby the valve is 60 opened and closed at properly timed intervals, a spring 33 engaging the bent extremity of each stem 31 at one end while its opposite end engages the inner extremity of the casing 28 of the valve. Furthermore, 65 the intake chamber 27 is in communication through a conduit 34 with an intake port 35 communicating with the outer portion of the cylinder and so arranged that as the piston approaches its inward limit of movement the explosive mixture which has entered the inner extremity of the cylinder through the port 26, will first be compressed and afterward passed by way of the conduit 34 into the cylinder chamber outwardly 70 beyond the piston, after which the piston again moves outwardly. A check valve 37 is employed to introduce atmospheric air into each induction conduit 34 during the outward movement of the piston, the casing 39 being connected with the wall of the cylinder through the medium of a nipple 40 which is threaded into an opening which intersects the outer extremity of the passage through the conduit 34. A spring 38 located 75 within the casing 39 acts upon the check valve 37 to hold the latter normally closed against the entrance of atmospheric air through a small passage 41.

The function of this check valve construction is to introduce atmospheric air into the conduit 34 during the outward movement of the piston, the suction in the inner extremity of the cylinder chamber serving not only to draw a charge of explosive mixture thereinto, but also serving to unseat the check valve 37 and allow the conduit 34 to fill with atmospheric air, so that as the charge of explosive mixture from the inner extremity of the cylinder starts toward the outer extremity of the cylinder through the conduit 34, a column of atmospheric air in the conduit 34 will be in front of it. The cylinder is also provided with an exhaust port 42 which begins to open slightly in advance of the intake port 35 during the inward movement of the piston. This exhaust port is in communication with an exhaust conduit or manifold 43 which may be suitably positioned and arranged with reference to the 80 convenient discharge of the refuse products of combustion when the engine is in use.

The other extremity of the piston is provided with an outer projection 44 which is curved to form in conjunction with the adjacent wall of the cylinder a space 45 which is open toward the outer extremity of the cylinder. Hence, during the inward movement of the piston after each explosion which occurs at the outer extremity of the 85

cylinder, the exhaust port is first partly uncovered and the exhaust through the conduit or manifold 43 commences, and immediately afterward a column of air from the conduit 34 begins to enter the cylinder through the uncovered port 35, said column of air entering the cylinder in advance of the explosive mixture from the inner extremity of the cylinder, the column of air being deflected outwardly by the projection 44 and acting on the refuse products of combustion to scavenge the explosion compartment of the cylinder, whereby there is a layer or stratum of atmospheric air between the explosive mixture and the refuse products of combustion as the explosive mixture is entering the outer or explosion compartment of the cylinder. This explosive mixture as it enters the cylinder immediately engages the deflector 44 of the piston and is directed outwardly toward the outer extremity of the cylinder, and by virtue of this construction the explosive mixture first passes to the outer extremity of the cylinder and by virtue of this fact gets beyond, so to speak, the aforesaid stratum of air and as the explosive charge continues to enter the cylinder it facilitates the scavenging of the cylinder of the burned gases. Then, during the return or outward movement of the piston, the charge of explosive mixture is compressed and exploded. As illustrated in the drawing the outer portions of the cylinders, or those which correspond with the compartments where the explosions occur, are surrounded by a water jacket 46 having an inlet conduit 47 and an outlet conduit 48 for maintaining the circulation. The chambers 49 in which the spark plugs 44 are located are also surrounded by a water jacket 50 which is a part of the water cooling system of the structure, since the water jackets 46 and 50 are in communication with each other by means of perforations 51.

From the foregoing description the use and operation of my improved engine will be readily understood. The explosions in the different cylinders of the engine, will, of course, be properly timed to produce the best results, or so that explosions in no two of the cylinders occur at the same time.

The operation of the engine so far as the novel features are concerned, will be understood by direct reference to the mechanism of a single cylinder. For instance, if I assume that the piston in the right hand cylinder of the two shown in section in Fig. 1 is at its inward limit of movement, as shown in the drawing, as it begins its outward travel, it will draw a charge of explosive gas into the end of the cylinder adjacent the crank case through the induction port 26, and this will continue until the piston reaches its outward limit of movement. At the same time the conduit 34 is filled with atmospheric air which enters said conduit through the small port 41, the valve 37 having been unseated by the suction in the inner compartment of the cylinder, this filling of the conduit with the atmospheric air occurring simultaneously with the filling of the inner compartment of the cylinder with explosive mixture through the port 26. During the return movement of the piston the valve 28 which controls the said inlet port will remain closed by virtue of the tension of the spring 33 and the pressure in the inner compartment of the cylinder. Hence, the charge of explosive mixture in the end of the cylinder adjacent the crank case will be compressed until the piston has moved inwardly far enough to uncover or open the outer intake port 35. As soon as this occurs the charge of explosive mixture starts toward the outer or explosion compartments of the cylinder but drives the column of atmospheric air in the conduit 34 ahead of it. Hence, this column of air enters the outer compartment of the cylinder in advance of the charge of explosive mixture and separates said charge from the refuse products of combustion during the scavenging operation, whereby by the time the cylinder is thoroughly scavenged its outer or explosion compartment will be filled with explosive mixture ready for compression. Then, as the piston begins its outward movement, it will again compress the charge of explosive mixture in the outer end of the cylinder and the charge will then be ignited. During the inward movement of the piston another charge of gas or another charge of explosive mixture is compressed within the inner portion of the cylinder and the conduit 34 again filled with atmospheric air, and as soon as the induction port 35 is again uncovered, the column of air and the explosive mixture rush into the outer portion of the cylinder and aid in driving out the refuse products of combustion as heretofore explained, these products passing through the exhaust port 42 and finally through the exhaust manifold 43.

From this it will be understood that each charge of explosive mixture is twice compressed within the cylinder. First, during each inward movement of the piston and afterward during the outward movement of the piston, the charge of explosive mixture in the meantime having passed from the inner or crank case end of the cylinder into the outer or spark plug extremity thereof. By virtue of the extra or first compression of the charge of explosive mixture, the gasoline or other fuel is mingled with the air or oxygen element in a most thorough and efficient manner, whereby the explosive charge is properly vaporized, before entering the explosion compartment of the cylinder; as soon as it does enter said compartment 130

ment and is compressed by the return movement of the piston, it is in perfect condition to give the best results as soon as the explosion takes place.

5 Attention is called to the fact that my improved construction is a two-cycle engine having the inner extremities of the cylinders closed or shut off from the crank case, thus making it practicable to compress explosive mixture in the inner extremity of each cylinder. By virtue of this closure the inner extremities of the cylinders, whereby they are cut off from the crank case, except so far as is required in order 10 that the piston stems may be operatively connected with the crank shaft, it becomes absolutely impossible for any excess of gasoline which may enter the cylinders and be unburned therein from passing into the 15 crank case and vitiating the lubricating material therein. For instance, on a cold day the practice is to open the choker to give a free flow of gasoline for an easy start and the driver frequently leaves the choker open. The result is a too free flow of gasoline which does not explode but goes over 20 the piston and down into the lubricating oil where the construction will permit of such passage. Where the plunger type of pump 25 is used it will not operate when the lubricant is thin and the oil will not siphon. The result of this is bad lubrication or no lubrication at all and serious trouble frequently results.

30 35 With my improved construction it becomes impossible for any excess of gasoline in the cylinders to find its way into the crank case, and by reason of the fact that the charge of explosive mixture is first taken 40 into the inner extremity of the cylinder before entering the outer or explosion compartment, if there is any excess of gasoline in the cylinders, it will be utilized with the regular charge and carried to the explosion 45 compartment of the cylinder. Hence, if there is an excess of gasoline in the cylinders it will be advantageously utilized in my improved construction, whereby there will be no loss in this regard, while in the ordinary construction of engine this excess of 50 gasoline in the cylinders is worse than a loss since it vitiates the lubricating oil in the crank case and renders it unfit for use.

Having thus described my invention, what I claim is:

1. In an internal combustion engine, a cylinder, a piston adapted to reciprocate therein, the cylinder being offset at an intermediate point and one end of the piston being offset annularly to fit therein, a combustion chamber being provided above the piston and a compression chamber being provided below the piston and offset end portion thereof, there being a connecting passage between said chambers, the space between said offset cylinder portion and said offset piston end portion being free of communication with each of said chambers, a piston rod for operating said piston, a sleeve united with the bottom of said compression chamber to make a gas-tight joint, a sleeve surrounding said rod and extending from the bottom of the compression chamber up into said piston, the lower end of the piston being closed between the cylinder wall and the sleeve, the lower end of the compression chamber having a fuel-intake passage leading thereinto. 65
2. In an internal combustion engine, a cylinder, a piston attached to reciprocate therein, a combustion chamber being provided above the piston and a compression chamber being provided below the piston, there being a connecting passage between 70 said chambers, a piston rod for operating said piston, a sleeve united with the bottom of said compression chamber to make a gas-tight joint, a sleeve surrounding said piston rod and extending from the bottom of the compression chamber up into said piston, the lower end of the piston between the cylinder wall and the sleeve being closed to 75 the passage of gas, the lower end of the compression chamber having a fuel-intake passage leading thereinto. 80

In testimony whereof I affix my signature.

HERBERT L. MEEDER.
